Patented Aug. 6, 1974

232,316

GOLF PUTTER HEAD

Raymon W. Cook, 406 Top Hill,
San Antonio, Tex. 78209

Filed Sept. 29, 1972, Ser. No. 293,525

Term of patent 14 years

Int. Cl. D21—02

U.S. Cl. D34—5 GH

FIG. 1 is a front elevational view of a golf putter head showing my new design.

FIG. 2 is a front end view of FIG. 1.

FIG. 3 is a top plan view of FIG. 1.

FIG. 4 is a rear elevational view of FIG. 1.

FIG. 5 is a bottom plan view of FIG. 1.

I claim:

The ornamental design for a golf putter head, as shown.
